ASH TRAY

Paul V. Vasile, 6134 Kirkwood, Ave., Chicago, Ill.

Filed Aug. 13, 1962, Ser. No. 71,244

Term of patent 14 years

(Cl. D85—2)

FIG. 1

FIG. 2

FIG. 3

I claim:

The ornamental design for an ash tray, as shown.
